UNITED STATES PATENT OFFICE

HERBERT G. MACKINNEY, OF PROVIDENCE, RHODE ISLAND.

DESIGN FOR A BRACELET-CHARM.

SPECIFICATION forming part of Design No. 13,368, dated October 24, 1882.

Application filed June 27, 1882. Term of patent 3½ years.

To all whom it may concern:

Be it known that I, HERBERT G. MACKINNEY, of the city and county of Providence, and State of Rhode Island, have invented and produced a new and original Design for an Ornament or Charm for Bracelets, Watch-Chains, and other Articles of Jewelry, of which the following is a specification, reference being had to the accompanying drawing, forming a part hereof.

The leading features of said design consist of a transparent body representing a miniature aquarium, showing within its substance representations of some or all of the usual contents of an aquarium.

The accompanying drawing is deemed sufficient to fully illustrate my said design, and represents a solid body of transparent substance, T, with the forms of fishes, F, in the substance of the same, which may be painted to represent the natural colors, and the forms of vegetation, V, also fixed in the appropriate part of body T and colored as desired, presenting a natural appearance in miniature when viewed through the transparent substance T. To this may be added the mineral and other objects appropriate to be placed in an aquarium likewise fixed in the body of the material, and my design may be further varied by adding to the fishes or substituting therefor other aquatic animals. Ornamentation appropriate to the imitation of parts usual to an aquarium—as metallic joints, solid floor or bottom, (shown in drawing as B,) &c.— is affixed to the outside of body T, and the whole, representing an aquarium, arranged as shown in the drawing, to be suspended by chain C or other appropriate means from a bracelet or watch-chain, or otherwise attached to any article of jewelry.

The precise form here shown is not necessary as part of my design, and I propose constructing this design with variations by combining more or less, as desired, of the features herein described.

What I claim, and desire to secure by Letters Patent, is—

1. The design for an ornament or charm for bracelets, watch-chains, and other articles of jewelry to which it may be appropriate, herein shown and described, the same consisting of the body T and fishes F, arranged to present the appearance herein described.

2. The design for an ornament or charm for bracelets, watch-chains, and other articles of jewelry to which it may be appropriate, consisting of the transparent body T, with appropriate figures of aquatic animals and of vegetation, represented as described in said body.

3. The design for an ornament or charm for bracelets, watch-chains, and other articles of jewelry to which it may be appropriate, consisting of a transparent body ornamented on the outside with figures representing fixtures appropriate to an aquarium, and with figures fixed in the substance of said body, as herein described, representing the animal life and other objects usually found in an aquarium.

4. The design for an ornament or charm for bracelets, watch-chains, or other articles of jewelry to which it may be appropriate, formed substantially as herein described, and representing an aquarium.

HERBERT G. MACKINNEY.
